(57) **CLAIM**

The ornamental design for an on-vehicle speaker, as shown and described.

DESCRIPTION

FIG. 1 is a right, front, and top perspective view of the first embodiment of an on-vehicle speaker;

FIG. 2 is a left, rear, and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and

FIG. 8 is a right side elevational view thereof.

FIG. 9 is a right, front, and top perspective view of the second embodiment of an on-vehicle speaker;

FIG. 10 is a left, rear, and top perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a left side elevational view thereof; and,

FIG. 16 is a right side elevational view thereof.

The broken lines shown in the drawings illustrate portions of the on-vehicle speaker that form no part of the claimed design.
